(57) **CLAIM**

The ornamental design for a display screen or portion thereof with graphical user interface as shown and described.

DESCRIPTION

FIG. 1 is a front view of a display screen or portion thereof with graphical user interface showing our new design; FIG. 2 is another front view thereof shown in a different broken line environment; and,

FIG. 3 is an enlarged view of the area 3 indicated by the single dot-dash broken lines in FIG. 1.

The evenly-spaced broken lines depict portions of the display screen or portion thereof that form no part of the claimed design. The remaining evenly-spaced broken lines showing portions of the graphical user interface form no part of the claimed design. The rectangle indicated by the single dot-dash broken lines shown in FIG. 1 and FIG. 3 illustrate the boundary of enlarged area of the design. The "3" indicia and splined curve indicated by the single dot-dash broken lines in FIG. 1 identify the enlarged area. The single dot-dash broken lines form no part of the claimed design.
